UNITED STATES PATENT OFFICE.

FRITZ SCHLENDER, OF BERLIN-HOHENSCHONHAUSEN, GERMANY, ASSIGNOR TO CLUSOR G. M. B. H., OF BERLIN, GERMANY, A CORPORATION OF GERMANY.

DEVICE FOR BINDING PAPER SHEETS.

Application filed October 15, 1927, Serial No. 226,492, and in Germany June 25, 1925.

This invention relates to a device for binding together superposed sheets of paper by passing them between two interengaging members, preferably two interengaging 5 wheels having tooth-like projections and correspondingly shaped tooth spaces thereon, both members being pressed together and acting with that pressure upon the superposed sheets to cause them to stick together 10 along a line.

It has now been ascertained that the capacity of such a device may be increased considerably if the toothlike projections upon the wheels are provided with flat 15 slopes or bevels extending from the crown or crest of the tooth towards both sides. According to another embodiment of the invention the flat slopes adjacent to the crown of the tooth are continued by steeper slopes 20 adjacent to the sides of the wheel.

In the drawing affixed hereto and forming part of the specification

Figure 1 is a binding machine with toothed wheels according to the invention 25 in side-elevation,

Figure 2, the same in front-elevation,

Figure 3, illustrates a binding wheel according to the invention on an enlarged scale, in side-elevation,

30 Figure 4, a further design of such a wheel likewise in side-elevation,

Figure 5, shows a further design of a binding wheel in side-elevation on an enlarged scale,

35 Figure 6, the front elevation of the wheel in Figure 5, and

Figure 7, a cross-section through this binding wheel along the line 7-7.

Referring to Figures 1 and 2 of the drawing 40 10 is the frame or standard of the machine in which are journaled the binding wheels 11 and 12 and which may be mounted on a table or bench by means of a screw clamp 25 or in any other suitable manner.

45 The binding wheel 11 is, for instance, rotated by a handle 13 clamped to the spindle 21, the wheel being mounted upon the free end of said spindle by means of a key or of a split-pin 19 passing through its hub 15.

50 The other of the pair of binding wheels 12 is adapted to turn freely upon a shaft 26 and is secured against axial displacement by a collar 17 held in place by a split-pin 18. In the embodiment illustrated in Figures 1 and

55 2 of the drawing the two binding wheels

are resiliently forced towards each other in such a way, for instance that the shaft 26 is mounted upon an eccentric disc 27 which by means of eccentric shaft 28 and the springy lever 29 is moved in such a manner that the pressure between both wheels may vary resiliently. The pressure may be adjusted by a spring 29 bearing against a set screw 30 mounted in an abutment 31. Adjacent to the place of engagement of the two 60 wheels there is located an operating table 14 through a slot 33 of which the binding wheels 11, 12 interengage and which serves to guide the superposed sheets of paper to be sticked together.

65 The binding wheels according to the invention are shown on an enlarged scale in the Figures 3 to 6 of the drawing. The wheel illustrated may serve as the driven wheel 11 of the Figures 1 and 2 or equally 70 well as counter or entrained wheel 12. The two wheels may be identical as regards diameter, pitch and arrangement of the teeth or they may differ in diameter and arrangement of the teeth.

75 In the wheel illustrated in Figure 3 of the drawing the teeth are indicated by the reference numeral 55 and the medial part or central portion of the crown of the tooth with the numeral 50. Towards the two faces 51, 52 of the wheel the central portion of the tooth is continued by flat bevelments, slopes 80 53, 54.

85 In the design of the wheel illustrated in Figure 4 the teeth are indicated by the reference numeral 66, the medial part or central portion of the tooth by the numeral 60, the bevels or slopes continuing directly towards both sides with 61, 62. These comparatively flat inclined bevelments or gentle 90 slopes are continued by further steeper bevels or slopes 63, 64. By the action of these wedgelike acting bevels or slopes the material located between the upsetting and the counterwheel is compressed in the direction 95 of the middle or central portion of the crown of the tooth so that the sheets up to a considerable number are reliably bound together. It has been ascertained that with the new or improved shape or configuration 100 of the teeth as herein described the upsetting or compressing pressure may be very considerably increased, for instance by employing very strong springs forcing the wheels together, without a cutting or tearing 105 110

2
of the sheets to be bound together. Although it is sufficient to provide a single bevelment, slope or incline 53, 54 or 61, 62 on each side of the tooth center line, it is preferable to carry out the bevelling or sloping of the teeth in such a manner that the pressure acting at the central portion of the tooth, for instance at 60 in Figure 4, decreases gradually or in steps towards the 10 root of the tooth. This end in view is attained by the steeper bevels, slopes or inclines 63, 64 forming a continuation of the flatter bevels, slopes or inclines nearer the centre line of the wheel.

15 A particularly advantageous arrangement results if the bevels, slopes or inclines are rounded or curved in their entire length or at least at their intersecting edges or the edges adjoining the central portion of the 20 crown of the tooth, as shown in Figure 1 or on an enlarged scale in the Figure 5 in side elevation and Figure 7 in cross-section. These roundings of the teeth 67 may be semi-circular or substantially so, as shown in the 25 Figures 5 and 7 at 65. This leads to a simple method of manufacturing these wheels, the wheel blank being first shaped along the circumference by means of a tool provided with a concave semi-circular cutting edge, where- 30 upon the teeth are milled or cut or otherwise produced in this profiled wheel blank.

It will be understood that the invention is 35 by no means limited to wheels with tooth-like projections only, but is equally well applicable to other members which may take the place of wheels in the device specified, such as racks or suitably shaped punches and the like.

Various modifications and changes may be 40 made without departing from the spirit and the scope of the invention, and I desire, therefore, that only such limitations shall be placed thereon as are imposed by the prior art.

45 I claim:

1. In a device for binding superposed sheets of paper together, two interengaging members having tooth-like projections and correspondingly shaped tooth spaces thereon 50 and acting with pressure upon the superposed sheets to cause them to stick together along a line, means for actuating said members, and means for pressing said members towards each other, said tooth-like projections having flat bevelments at their faces adjacent to their medial parts.

2. In a device for binding superposed sheets of paper together, two interengaging members having toothlike projections and correspondingly shaped tooth spaces thereon

and acting with pressure upon the superposed sheets to cause them to stick together along a line, means for actuating said members, and means for pressing said members towards each other, said tooth-like projections having flat bevelments at their faces adjacent to their medial parts, and steeper bevelments adjacent to said flat bevelments. 65

3. In a device for binding superposed sheets of paper together, two interengaging 70 members having toothlike projections and correspondingly shaped tooth spaces thereon and acting with pressure upon the superposed sheets to cause them to stick together along a line, means for actuating said members, and means for pressing said members towards each other, said toothlike projections being tapered at their ends, the steepness of taper 75 increasing from their medial parts to their bases. 80

4. In a device for binding superposed sheets of paper together, a frame, two interengaging wheels mounted thereon, said wheels having toothlike projections and correspondingly tooth shaped spaces thereon 85 and acting with pressure upon the superposed sheets to cause them to stick together along a line, means for rotating one wheel and means for pressing the wheels towards each other, said toothlike projections having flat bevelments at their faces adjacent to their medial parts. 90

5. In a device for binding superposed sheets of paper together, a frame, two interengaging wheels mounted thereon, said 95 wheels having toothlike projections and correspondingly tooth shaped spaces thereon and acting with pressure upon the superposed sheets to cause them to stick together along a line, means for rotating one wheel 100 and means for pressing the wheels towards each other, said toothlike projections having flat bevelments at their faces adjacent to their medial parts, and steeper bevelments adjacent to said flat bevelments. 105

6. In a device for binding superposed sheets of paper together, a frame, two interengaging wheels mounted thereon, said wheels having toothlike projections and correspondingly tooth shaped spaces thereon 110 and acting with pressure upon the superposed sheets to cause them to stick together along a line, means for rotating one wheel and means for pressing the wheels towards each other, said toothlike projections being 115 tapered at their ends, the steepness of taper increasing from their medial parts to their bases.

In testimony whereof I affix my signature.
FRITZ SCHLENDER.
